(57) **CLAIM**

The ornamental design for ink bottle for inkjet printer or portions thereof, as shown and described.

DESCRIPTION

FIG. 1 is a perspective view as viewed from front and top direction thereof of a neck part with ROM chip of an ink bottle showing our new design;

FIG. 2 is a front view of FIG. 1;

FIG. 3 is a rear view of FIG. 1;

FIG. 4 is a top view of FIG. 1;

FIG. 5 is a bottom view of FIG. 1;

FIG. 6 is a right side view of FIG. 1; and,

FIG. 7 is a left side view of FIG. 1.

The broken lines are for purposes of illustration only and form no part of the claimed design.
